United States Patent Office.

HENRY H. GRIDLEY, OF AUBURN, NEW YORK, AND MARY L. GRIDLEY,
OF BURLINGTON, NEW JERSEY.

Letters Patent No. 63,629, dated April 9, 1867.

IMPROVEMENT IN FRUIT-BOXES.

The Schedule referred to in these Letters Patent and making part of the same.

TO ALL WHOM IT MAY CONCERN:

Be it known that we, HENRY H. GRIDLEY, of Auburn, New York, and MARY L. GRIDLEY, of the city of Burlington, New Jersey, have invented a new and improved Method of Making Fruit-Boxes, of which the following is a full and exact description, reference being had to the accompanying drawing, and to the letters of reference marked thereon.

Figure 1 represents the shell of the box, ready to be locked together. It is made of veneer of any suitable thickness. It is perforated with slots and holes at various places, all which may be made by a punch at one blow, except the perforations A, which are described hereafter. The point B is cut into shape at the same time. The shell is now locked together by hooking the peculiarly shaped point B into the slot C, while the slot D at the same time catches the point E, and the whole is held firmly together by then inserting the slide-key F into the slots G. The shell thus formed is cup-shaped, so that the boxes will nest together. A bottom being dropped into the shell, the perforations A are made from its outside, so as to create numerous ragged projections on the inside of the same, just above the bottom, as seen at H, fig. 1. They are so numerous and prominent as to effectually prevent the bottom from falling out when the box is turned upside down. An additional aid to keeping the bottom in consists in having the shell made wet by soaking when locked together. The bottom being dry, the shell will naturally contract in drying, and will thus be shrunk on. The same advantageous result will be secured by using green wood for the shell. The whole forms a box cheap enough to be given away with the fruit, and strong enough to bear it hundreds of miles to market. A complete box is shown in fig. 2.

We claim the joining of the ends of the shell by hooking them together, as shown, and introducing a slide-key or other equivalent device, as described, to assist in keeping said ends firmly together.

Also, securing the bottom in its place by means of projections on the inside of the shell, formed from the material thereof, either above or below the bottom, or both above and below.

Also, the shrinking of the wet or green shell upon the dry bottom, when in combination with the above devices.

HENRY H. GRIDLEY,
MARY L. GRIDLEY.
